UNITED STATES PATENT OFFICE.

EDWARD W. WHITE, OF CHICAGO, ILLINOIS.

ROLLER-SKATE.

No. 901,136.

Specification of Letters Patent.

Patented Oct. 13, 1908.

Application filed March 14, 1908. Serial No. 421,142.

To all whom it may concern:

Be it known that I, EDWARD W. WHITE, a citizen of the United States, residing at Chicago, in the county of Cook and State of Illinois, have invented a new and useful Improvement in Roller-Skates, of which the following is a specification.

My invention relates to certain new and useful improvements in roller skates, and is 10 fully described and explained in the specification and shown in the accompanying drawing, in which:

Figure 1 is a side elevation of my improved device, a portion of the frame-work adjacent 15 to the rear wheels or rollers being broken away in a central vertical section; Fig. 2 is a bottom plan of the skate; Fig. 3 is a section in the line 3 of Fig. 1; and Fig. 4 is a transverse section in the line 4 of Fig. 1.

Referring to the drawings A is a base-plate upon which rests the foot of the user, the same being provided with the usual means for securing the same to the foot, this means being (in the form of device here 20 illustrated) a key-operated clamp at the front and a strap at the rear. It will of course be obvious that any other means for securing the base-plate to the foot or shoe can be adopted according to common practice in 25 the art, the skate attaching means forming no part of my present invention. Brackets b , b^1 are secured to the base-plate A, the same being arranged in pairs at front and rear and each bracket having a horizontal 30 portion secured to the base-plate and a vertical portion extending downward therefrom; the vertical portion of the brackets b^1 being longer than those of the brackets b as illustrated, and the two brackets b^1 being placed 35 adjacent to each other, so that the bracket b^1 is the rear one of the front pair and the forward one of the rear pair. The aforesaid brackets are provided in their vertical portions with vertically extending slots, through 40 which extend longitudinal and vertically movable pins B. Between each pair of brackets b , b^1 and above the pins B supported therebetween, is placed a block of rubber or other resilient material C, the lower surface 45 of which is channeled out to receive and fit the corresponding pin.

Two swivel-heads D are provided, each pivotally supported by the corresponding pin B. The construction of the swivel- 50 heads will be readily understood by reference to the drawings, from which it will be seen

that each comprises a cylindrical barrel d provided at its upper end with a flat plate d^1 and at its lower end with a downwardly projecting pin d^2 . The plate d^1 is provided at 60 front and rear with upwardly extending ears d^3 which surround the corresponding pin B, lying to the front and rear of the block C of rubber or resilient material, and it is likewise provided at the side with two smaller 65 ears d^4 which lie to the two sides of the block C to prevent the lateral displacement thereof. It will be evident that by this construction, the swivel-head D is provided with a bearing whereby it can be swung laterally 70 about the pin B as a center and that the block C is so arranged as to resist resiliently any upward pressure which may be exerted by the swivel-head D, the slots in the brackets b , b^1 permitting a limited vertical movement of the pin against the compression of the resilient block C. Upon the downwardly 75 projecting pin d^2 of each swivel-head D is journaled an axle E rotatable in a horizontal plane about said pin as a center, and said 80 axle supports at its ends rollers F of usual form.

The rear axle E is provided with a forwardly projecting pin e adapted to lie in a notch provided in the corresponding bracket 85 b^1 at the lower end of said bracket, while the forward axle E has a similar rearwardly extending pin, engaging with a corresponding notch in the forward bracket b^1 . As a result 90 of this construction it will be seen that the entire weight of the user is sustained by the resilient block C and any shock must be transmitted through said block to reach the base-plate A upon which the foot rests. As 95 a result, a skate is provided which is cushioned in its action and with which the user is to a large extent freed from the annoyance, jar and vibration common in skates of usual construction. Furthermore, the device can be readily and perfectly steered by leaning 100 the body to one side or the other in the usual manner. If for instance, the right hand side of the base-plate as viewed in Fig. 3 be pressed downward by the user leaning his weight to one side, the bracket b^1 will be 105 moved at its lower end toward the left with the result that the right-hand roller of the two shown will move forward relatively, while the one to the left will move backward, the same movement of the base-plate will produce a 110 reversed movement of the front axle, so that the axles will be set in proper position for

turning toward that side to which the pressure is applied. Thus when pressure is applied, say to the right side of the skate for turning to the right, the forward right hand roller will move backward and the forward left hand roller forward, while the backward right hand roller will move forward, and the left-hand backward roller backward, so that the rollers will tend to describe a curve in running upon a smooth surface. The device is thus not only provided with a perfectly cushioned set of rollers, but it has a simple and efficient steering mechanism fully under the control of the user in the simplest manner.

I realize that considerable variation is possible in the details of construction of my improved device, without departing from the spirit of my invention, and I do not intend, therefore, to limit myself to the specific form herein shown and described.

What I claim as new, and desire to secure by Letters Patent, is—

1. The combination with a base-plate and axles carrying rollers and adapted to support the base-plate, of a resilient support interposed between the axles and the base-plate and arranged to carry the entire weight thrown upon the base-plate, and means whereby the oscillation of the base-plate with respect to the plane of the axles will rotate said axles in opposite directions for steering purposes.

2. The combination with a base plate of two longitudinally extending pivots substantially parallel to the base-plate and bodily movable in a vertical direction with respect

thereto, resilient cushions interposed between said pivots and the base-plate and arranged to support the entire weight thrown upon the base-plate, swivel-heads pivoted to said pivots and oscillatable laterally about the same centers, axles pivotally supported by the swivel-heads and carrying rollers at their ends, and means whereby the lateral oscillation of the swivel-heads shall rotate the axles in opposite directions.

3. The combination with a base-plate, of two pairs of vertically slotted brackets secured to and projecting downward from the base-plate, the rear bracket of the front pair and the front bracket of the rear pair having openings near their lower ends, shafts supported in the slots of said brackets and extending longitudinally of the base-plate and vertically movable with respect thereto, resilient cushions interposed between the said shafts and base-plate, swivel-heads pivoted to said shafts and having a bearing upon the resilient cushions whereby they are normally held in central position, axles journaled to the swivel-heads and carrying rollers at their ends, and a rearward projection on the front axle and a forward projection on the rear axle engaging openings in the corresponding brackets, whereby oscillation of the base-plate with respect to the plane of the axles will rotate the axles to steer the skate.

Chicago March, 1908.

EDWARD W. WHITE.
